UNITED STATES PATENT OFFICE.

OWEN T. DOUGHERTY, OF ST. PAUL, MINNESOTA.

MISSILE-PROJECTING DEVICE.

Application filed August 12, 1924. Serial No. 731,617.

To all whom it may concern:

Be it known that I, OWEN T. DOUGHERTY, citizen of the United States, residing at St. Paul, in the county of Ramsey and State of Minnesota, have invented certain new and useful Improvements in Missile-Projecting Devices, of which the following is a specification.

This invention relates to missile projecting devices, and has for its object the production of an implement having in its main relations, purposes and uses, the nature of a toy, capable of propelling through the air with more or less directional accuracy or 10 precision projectile bodies of varying size and form. By the use of this invention a rod-like piece such as an arrow may be shot forth for a considerable distance. Again this invention may be employed to throw 15 rounded objects such as marbles, meaning the small porcelain spheres with which boys play games. In fact, this invention may be used to "play marbles." Or, any like small pieces may be selected and discharged at any 20 suitable mark or target. Another useful function of this invention comprises the killing of flies or other insects, by striking them with the movable head or terminal of the spring member, as hereinafter more 25 fully described.

This invention consists of parts having special construction, arrangement and operation, as illustrated in the accompanying drawings, of which Fig. 1 represents a side view of all parts assembled showing the spring in its contracted position. Fig. 2 shows the spring holder or barrel in longitudinal section with the spring extended, and an arrow in position to be thrown by 30 the spring. Fig. 3 is a section lengthwise of the combined parts as illustrated in Fig. 1. Fig. 4 is an end view looking at the lower end as the parts appear in Fig. 1, and showing the end provided with the finger-hold so-called for purposes of this description. Fig. 5 is a fragmentary view of the ends of the spring, showing the heads or terminals thereof, and the manner in which they are usually attached to the 40 spring ends.

Throughout the drawings and description the same letter is used to refer to the same part.

Considering the drawings, the holder or 45 barrel A is in practice a hollow tube of

turned wood having the form shown, but this invention is not intended to be limited to the specific shape delineated.

Movably in the bore or passage a of the holder A is a coil spring B somewhat longer than the holder as shown. Heads or terminals C and D engage the ends of the spring, and a preferred mode of securing the heads to the spring ends is set forth in Fig. 5, that is to say, the mode of attachment is to turn the inner annular edge, such as the edge d of the annular head D, outwardly over an end coil of the spring. It is believed to be clear that other methods may be followed for securing the terminals 60 to the spring ends. It will be noted best in Fig. 3, that the heads are larger than the bore or passage through the holder, and when the heads are attached, the spring is locked movably in the passage. To one end 65 of the spring the finger-hold E comprising a loop of wire, is suitably fastened, and it will be readily seen that if the notched end of the arrow shaft F be engaged with the loop E by passing the shaft lengthwise 70 through the coil spring, the spring may be extended as shown in Fig. 2, by grasping the holder in one hand and the end of the arrow between the thumb and fingers of the other hand. When freed, the arrow will be 75 shot forcibly through the spring and holder by which its movement is directed.

A marble G placed in the upper annular terminal C, may when the spring is drawn out by the loop and snapped back into place, 80 be thrown upwardly to a considerable distance. To play the game of marbles, wherein it is necessary to operate the holder in a horizontal attitude, a small catch plate or 85 table H with a ring clip h, to encircle the end of the holder as illustrated in Fig. 3, may be provided. In either arrangement, the marble is driven by a temporary extension of the spring which carries the terminal C for an instant some little distance beyond the end of the holder. The applicant's assumption is that this effect is caused by the momentum of the coils of the spring 90 acquired when it has been drawn out by the loop or finger-hold and released. By reason of the sudden meeting of the lower terminal D of the spring and the corresponding end of the holder, that end of the spring is 95 halted, but the remaining portion of the spring in rapid movement gains sufficient 100 105 110

momentum to throw the upper terminal C for an instant to some distance beyond the end of the holder as stated.

In explaining the operation of this invention it is thought that Fig. 2 and the foregoing statement will suffice, so far as the arrow is concerned. If a marble be placed on terminal C, and the spring snapped, it will be violently thrown from the terminal, and if the catch plate or concave table H is used, the holder may be held practically horizontal while the spring is manipulated. Or, the holder may be aimed at an insect, and the spring drawn out and then quickly released. The terminal C will jump as described from the end of the holder A, and strike the insect at some distance from the end of the holder, and in expert hands this peculiar use of this invention is especially effective.

Having now described this invention, and explained the mode of its operation, what I claim is:—

1. In a spring device for projecting missiles, the combination with a holder having a passage through it, of a coil spring movably occupying the said passage, a head or terminal attached to one end of the spring, the said head being larger than the mouth of the said passage, the other end of the spring having secured thereto a finger-hold whereby the spring may be elongated, the said head and the said finger-hold limiting the movement of the spring as a whole through the passage, whereby the release of the spring is followed first by a contractile action of the spring and then by temporary elongation thereof carrying the said head for a distance beyond the mouth of the said passage.

2. In a spring device for projecting missiles, the combination with a holder having a passage through it, of a coil spring movably occupying the said passage, an annular head or terminal attached to one end of the said spring, the said head being larger than the mouth of the passage thereby preventing the withdrawal of the spring as a whole in one direction, the other end of the spring having a finger-hold constructed to prevent

the removal of the spring as a whole in the other direction, the said finger-hold enabling the spring to be elongated, the release of the spring being followed by a contractile action of the spring and a temporary elongation thereof carrying the said head for a distance beyond the mouth of the said passage through the holder.

3. In a spring device for projecting missiles, the combination with a holder having a passage through it, of a coil spring occupying the said passage, an annular head or terminal attached to one end of the spring, the said head being larger than the mouth of the passage thereby preventing the withdrawal of the spring as a whole in one direction, the other end of the spring having a finger-hold comprising a wire loop and constructed to prevent the escape of the spring as a whole in the other direction, the said finger-hold enabling the spring to be elongated, the release of the spring being followed by a contractile action of the spring and a temporary elongation thereof carrying the said head for a distance beyond the mouth of the passage.

4. In a spring device for projecting missiles, the combination with a holder having a passage through it, of a coil spring occupying the said passage, an annular head or terminal attached to one end of the spring, the said head being larger than the mouth of the passage thereby preventing the withdrawal of the spring as a whole in one direction, a table supported by the holder adjacent the said head whereby a rounded projectile may be carried against the head with the holder horizontal, the other end of the spring having a finger-hold constructed to prevent the removal of the spring as a whole in the other direction, the said finger-hold enabling the spring to be elongated, and the release of the spring being followed by a temporary elongation thereof carrying the said head for a distance beyond the mouth of the said passage and acting forcibly upon the projectile.

In testimony whereof I affix my signature.

OWEN T. DOUGHERTY.
